(54) **WRITING, MODE OF TEACHING**

(76) Inventor: **Samuel Randall**

Samuel Randall
Inventor

The Schedule referred to in these Letters Patent and containing
part of the same continuing its description in the words of the said
Samuel Randall himself of his improvement in the art
of Penmanship.

The Alphabets large, small and Capital, or what
ever it may be termed the scholar or pupil should practice upon
paper on a slate as follows by a small or mark as easily
to be seen by the pupil, who is to trace and copy and letters with
a pencil taking care to appoint the time, the pupil going
through the copy the letters which being made with his pencil
are blotted with a sponge or cloth or otherwise but when
these letters remain for the pupil to trace over again and
again & by which he soon obtains the proper shape and
slant of every letter which is by far the most difficult part in
the process of obtaining the art of writing.

The process or paper is somewhat similar. Whatever is intended for
the pupil to write is composed on the paper from the copy of the
slate in a fine hair stroke, as the one we have made except
the line on top which is to be smudged to proper length for the pupil
to copy the letters by the hair letters below being designed to guide him
to the proper shape and slant of the letters only. In short the art
consists in tracing on a slate with a pencil, or on paper with
a pen, letters previously formed in a hair stroke as stated above.
Which will give the name of tracography.
